To all whom it may concern:

Be it known that I, JOHN W. This invention relates to a new and original design for emblems, such as badges, buttons, watch fobs and the like.

The drawing is a top plan of an emblem showing my new design made somewhat in the form of a shield, the upper portion of which is provided with a red panel —1—, a

white panel —2— and a blue panel —3— in which are printed respectively the letter —F—, the word —of— and the letter —A—, the lower portion having a somewhat oval panel in which is impressed the head of an elk.

What I claim is—

The ornamental design for an emblem as shown.

In witness whereof I have hereunto set my hand on this 31st day of August 1910.
